CLOCK-MECHANISM FOR AUTOMOBILES
AND THE LIKE

Richard H. Whitehead and Wilson E. Porter,
New Haven, Conn., assignors to The New
Haven Clock Company, New Haven, Conn., a
corporation

Application December 4, 1930. Serial No. 499,983

8 Claims. (Cl. 58—46)

This invention relates to an improvement in clock-mechanisms for automobiles and the like, and has for its main object the provision of a durable reliable and convenient clock-mechanism for automatically effecting the winding of a time-piece as an incident to steering.

A further object of our invention is to provide a simple and convenient arrangement of parts, whereby a clock may be employed as an operating-member for an electric switch, such as the horn-switch of an automobile.

With the above and other objects in view as will appear from the following, our invention consists in the combination and arrangement of parts which will be hereinafter described and particularly recited in the claims.

In the accompanying drawings:

Fig. 1 is a top or plan view of the steering apparatus of an automobile equipped with an automatically-wound clock in accordance with our invention;

Fig. 2 is a broken transverse sectional view taken on the line 2—2 of Fig. 1 but on a larger scale;

Fig. 3 is a broken view partly in horizontal section on the line 3—3 of Fig. 2 but showing the front movement-plate in elevation, with the movement-train shown by broken lines;

Fig. 4 is a vertical transverse sectional view corresponding to Fig. 2 but on a larger scale and showing, in addition, the clock-movement and some of the associated parts in section;

Fig. 5 is a broken detail sectional view of the driving-spring and spring-barrel, etc., taken on the line 5—5 of Fig. 4;

Fig. 6 is a detached perspective view of the winding-pinion provided with ratchet-teeth; and

Fig. 7 is a similar view of the reciprocating ratchet-member.

The embodiment of our invention herein chosen for illustration consists of a cup-shaped sheet-metal clock-case 10 housing a clock movement which will be shortly described and which clock-case 10 is closed at its upper end by means of a bezel 11 carrying a crystal 12.

The cup-shaped case 10 extends into an upwardly-opening cylindrical chamber 13 formed in the upper face of a steering-column head 14 formed of insulating material. Located in the chamber 13 and bearing against the bottom thereof and against the under-side of the case 10 so as to exert a constant effort to force the latter outward, is a helical spring 15 which is adapted to yield under manual pressure applied to the crystal 12 of the clock to permit the same

to move inward to close a circuit, as will herein-after appear.

The steering apparatus with which the clock may be associated in carrying out our invention, may be of any approved type but as herein shown consists of the head 14 already referred to which is mounted by means of one or more screws 16 upon the flanged upper end 17 of a stationary tube 18 which extends inside of the usual rotatable hollow steering-shaft or steering-tube 19 from which it is slightly spaced by means of a bushing 20, as shown in Figs. 2 and 4 of the drawings.

The upper portion of the steering-tube 19 is tapered to receive the hub 21 of a steering-wheel 22, the two latter members being secured together by means of screws 23. The hub 21 is formed with a keyway 24 receiving the outer portion of a substantially-semicircular key 25 seated in an arcuate groove 26 in the outer face of the steering-tube 19. The extreme upper end of the steering-tube 19 is reduced in diameter to form an upstanding externally-threaded neck 27 having threaded thereon a retaining-nut 28 which latter, in turn, is provided with an upstanding annular flange 29 upon which is firmly secured, in any approved manner, such as by shrinking, a ring-gear 30 which serves to wind the clock-movement housed within the casing 10, as will hereinafter appear.

Extending downward through the interior of the stationary tube 18 is a light-switch control-tube 31 provided at its upper end with a radial operating-lever 32 and having passing through its interior a throttle-control tube 33 provided with an operating-lever 34.

The throttle-lever 34 just above referred to is complemented by a spark-control 35 offsetting from the upper end of a spark-control-tube 36 extending downward through the interior of the throttle-control tube 33. Extending downward through the interior of the spark-control-tube 36 is an electric conductor 37 which leads to a warning signal such as a horn or the like, and has its upper end electrically connected to a terminal 38 mounted in the steering-column head 14, as shown in Figs. 2 and 4, in position to be engaged by a movable contact 39 secured to the under-face of the casing 10 of the clock.

As before pointed out, the casing 10 is constantly urged outward by the helical spring 15 which latter serves to normally keep the contact 39 out of engagement with its complementary contact 38. The outward movement of the casing 10 under the urge of the spring 15 is limited

by providing it in its periphery at two diametrically-opposite points with slots 40, each of which receives the reduced inner end of a stop-screw 41 diametrically threaded into the upper portion of 5 the steering-column head 14.

The ring-gear 30 before referred to, which is carried by and rotates with the steering-tube 19, meshes into a pinion 42 secured to the lower end of a clock-winding shaft 43 rotating in a tubular 10 bearing-stud 44 upstanding from the flanged upper end 17 of the stationary tube 18. The upper end of the winding-shaft 43 is provided with an upstanding tang 45 entered into a diametrical groove 46 formed in the lower end of a ratchet-member 47.

The ratchet-member 47 is formed upon its upper face with ratchet-teeth 48 and is mounted for rotation and limited reciprocation upon a stud 49 depending from a movement-plate 50 constituting the rear movement-plate of the clock-movement housed within the casing 10. The said ratchet-member 47 is encircled by a helical spring 51 bearing at its lower end against the inner face of the bottom-wall of the case 10 and 20 at its upper end against a thrust-washer 52 mounted upon the said ratchet-member and exerts a constant effort to hold the ratchet-teeth 48 in engagement with complementary ratchet-teeth 53 formed upon the under-face of a winding-pinion 54 which is mounted with freedom 25 for rotation upon the stud 49 already referred to.

The winding-pinion 54 meshes into and drives a winding-wheel 55 secured to the lower end of a winding-arbor 56 which bears in the rear movement-plate 50 and also in a complementary front movement-plate 57, as clearly shown in Fig. 4 30 of the drawings.

The winding-arbor 56 has staked upon it a hub 58 to which is coupled, by means of a pin 40 59, the inner end of a spiral spring 60. The spring 60 is housed within a spring-barrel 61 mounted upon the winding-arbor 56 with freedom 45 for relative rotation with respect thereto and which spring-barrel 61 is provided with gear-teeth 62 for driving a center-pinion 63 of the clock and through the intermediary of the same to cause the spring 60 to effect the driving of the clock-movement, which may be of any 50 approved type, and herein requiring no detailed description.

The spiral spring 60 effects the driving of the spring-barrel 61 by virtue of the fact that its outer convolution is frictionally engaged with the inner surface of the said barrel and is free 55 to slip with respect thereto when the spring has been wound to a predetermined tension. In order to enhance the frictional grip of the outer convolution of the spring 60 upon the inner surface of the spring-barrel 61 we secure to the said 60 outer convolution, by means of rivets 64, a flexible reinforcing strip 65 which in effect converts the outer convolution of the spring into a double-ply terminal.

Coming now to the operation for automatically winding the spring 60, it will be noted that upon every counter-clockwise rotation of the steering-wheel 22, the ring-gear 30 will be correspondingly turned and through the intermediary of the pinion 42, winding-shaft 43, ratchet-member 47, pinion 54 and winding-wheel 55, the spring 60 will be wound more or less, dependent upon the degree of counter-clockwise movement of the steering-wheel.

When the steering-wheel is turned in a clockwise 70 direction, the ratchet-teeth 48 of the ratch-

et-member 47 will ride idly back over the teeth 53 of the pinion 54.

When the spring 60 has been wound to a predetermined extent, its convolutions will so contract as to relieve the frictional grip of its outer convolution upon the inner surface of the spring-barrel 61, with the result that slippage will take place. Thus, despite continued rapid movements of the steering-wheel, the spring 60 will automatically prevent itself from being over-wound. 80

When it is desired to have the movable contact 39 engage the fixed contact 38, so as to complete a circuit to a signal device through the wire 37, an inward pressure upon the outer face of the crystal 12 will cause the clock, as a whole, to move inward against the counter-urge of the spring 15. This movement is permitted by the slots 40 in the periphery of the case 10 and by the fact that the groove 46 in the ratchet-member 90 95 47 is of ample depth from top to bottom.

As herein shown and described, the clock is wound by a counter-clockwise movement of the steering-wheel but it is obvious, without further illustration, that it may be wound by a clockwise movement or by both if desired. 100

It will be understood by those skilled in the art that our invention may assume varied physical forms without departing from our inventive concept, and we, therefore, do not limit ourselves to the specific embodiment herein chosen for illustration, but only as indicated in the appended claims. 105

We claim:

1. The combination with the steering-apparatus of an automobile or the like; of a spring-driven clock; and a winding-connection between the said steering-apparatus and the said clock; whereby the winding of the latter will be automatically effected as an incident to steering. 110

2. The combination with the steering-apparatus of an automobile or the like; of a spring-driven clock; and a winding-connection between the said steering-apparatus and the said clock including a ratchet-mechanism; whereby the 115 winding of the clock will be automatically effected as an incident to steering.

3. The combination with the steering-apparatus of an automobile or the like; of a spring-driven clock having a frictionally-coupled driving-spring; and a winding-connection between the said steering-apparatus and the said driving-spring; whereby the winding of the latter 120 will be automatically effected as an incident to steering. 125

4. The combination with the steering-apparatus of an automobile or the like; of a spring-driven clock having a frictionally-coupled driving-spring; and a winding-connection between the said steering-apparatus and the said driving-spring including a ratchet-mechanism; whereby the 130 winding of the said spring will be automatically effected as an incident to steering.

5. The combination with the steering-wheel and steering-shaft of an automobile or the like; of a spring-driven clock mounted in front of the said steering-wheel; and a winding-connection between the said steering-shaft and the said clock; whereby the winding of the latter will be automatically effected as an incident to the 135 movement of the said steering-shaft.

6. The combination with the steering-wheel and steering-shaft of an automobile or the like; of a spring-driven clock mounted in front of the said steering-wheel; and a winding-connection, 140 145 150

including a ratchet-mechanism, between the said steering-shaft and the said clock; whereby the winding of the latter will be automatically effected as an incident to the movement of the said steering-wheel.

7. The combination with the steering-wheel and steering-shaft of an automobile or the like; of a spring-driven clock having a frictionally-coupled driving-spring and mounted in front of the said steering-wheel; and a winding-connection between the said steering-shaft and the said clock; whereby the winding of the latter will be automatically effected as an incident to the movement of the said steering-shaft.

15

8. The combination with the steering-wheel and steering-shaft of an automobile or the like; of a spring-driven clock having a frictionally-coupled driving-spring and mounted in front of the said steering-wheel; and a winding-connection, including a ratchet-mechanism, between the said steering-shaft and the said clock; whereby the winding of the latter will be automatically effected as an incident to the movement of the said steering-wheel.
